DESIGN FOR AN INSTRUMENT CASE OR SIMILAR ARTICLE

William A. Baum, Forest Hills, N. Y.

Application January 13, 1934, Serial No. 50,397

Term of patent 7 years

To all whom it may concern:

Be it known that I, WILLIAM A. BAUM, a citizen of the United States, residing at Forest Hills, in the county of Queens and State of New York, have invented a new, original, and ornamental Design for an Instrument Case or Similar Article; of which the following is a specification, reference being had to the accompanying drawing, forming part thereof, wherein—

Figure 1 is a plan view of the case.

Figure 2 is a side elevation.

Figure 3 is a front end elevation.

Figure 4 is a perspective, and

Figure 5 is a section on an enlarged scale taken as indicated by the line 5—5 of Figure 2.

I claim:

The ornamental design for an instrument case or similar article substantially as shown.

WILLIAM A. BAUM.
